UNITED STATES PATENT OFFICE.

WALTER P. MURPHY, OF NEW YORK, N. Y.

CAST-METAL DOOR FOR RAILWAY CARS OF THE DUMPING TYPE.

Application filed May 17, 1920. Serial No. 381,992.

To all whom it may concern:

Be it known that I, WALTER P. MURPHY, a citizen of the United States, residing at New York city, in the county of New York and State of New York, have invented certain new and useful Improvements in Cast-Metal Doors for Railway Cars of the Dumping Type, of which the following is a specification.

10 My invention relates to the construction of railway cars of the dumping or drop bottom type such as hopper cars, hopper gondola cars, drop bottom or general service gondola cars, or the like; and the principal 15 object of the invention is to provide a door or drop bottom element for cars of this general class which will be very strong and rigid, without being excessively heavy, and which will have a smooth upper or inner 20 surface so that there will be no chance for water to be trapped and so that as the load in dumping passes over it, no obstruction will be presented to the sliding movement of the material.

25 The invention is illustrated, in certain preferred embodiments, in the accompanying drawings, wherein—

Fig. 1 is a fragmentary plan view of one end of a drop bottom or general service gondola car furnished with doors constructed in accordance with my invention.

Fig. 2 is a sectional view on line 2—2 of Fig. 1, the scale being considerably enlarged.

Fig. 3 is a perspective view of one of the 35 doors seen from below.

Fig. 4 is an inverted plan view of a modified form of door in which the arrangement of the strengthening webs on the under side of the door is different from that shown in 40 the first three figures.

Figs. 5, 6, 7, 8 and 9 are similar views showing different arrangements of the strengthening webs.

Referring first to Figs. 1, 2 and 3, the 45 side walls of the car are shown at 10 and the end wall at 11. 12 is the center sill to which doors 13, 13 are hinged. Each of these doors is composed of an integral casting having a smooth upper face 14 and depending marginal flanges 15, 16, 17 and 18. 50 19, 19 are hinge lugs formed on flange 15. The structure is rigidified by means of a plurality of webs cast integral with the door which project from the under surface

of the door and preferably radiate from a 55 boss 20, webs 21 extending to the corners of the door and webs 22 to the side marginal flanges. In addition there may be a number of shorter triangular webs 23. Preferably the webs are deepest at the center of 60 the door and taper down to the width of the marginal flanges into which they merge. In order to provide additional strength at the hinges a pair of webs 24, 24 bridge the space between the marginal flange 15 and 65 the adjacent diagonal webs 21 near each hinge lug. The fixed members 25 of the hinges are fastened to the center sill of the car, this structure comprising a T iron, the flanges 26 of which overlap the inner 70 edges of the doors.

In the arrangement shown in Fig. 4 the door 13^a is provided with longitudinally extending strengthening webs 27 and transverse webs 28, the latter aligned with the 75 hinge lugs 29.

In Fig. 5 the door 13^b is formed with a pair of transverse webs 30 aligned with the hinge lugs 31. The space between webs 30 is reinforced by a pair of intersecting webs 80 32, 32 and the spaces outside of webs 32 by diagonal webs 33.

In Fig. 6 the door 13^c is formed with a plurality of webs 34 which extend in a fan-like arrangement from the portion of the 85 door between the hinge lugs 35.

In Fig. 7 a door 13^d is shown having two pairs of curved webs 36, 36, the webs of each pair coming together at the hinge lugs 37 and at a point on the opposite edge of the 90 door.

In Fig. 8 the door 13^e is formed with a large circular boss 38 and strengthening webs 39 extending outwardly from the boss.

In Fig. 9 the door 13^f has a long web 40 95 extending from each hinge lug 41 to the remote corner of the door and a short web 42 from the hinge lug to the adjacent end of the door, in addition to which there are two diagonal webs 43 extending across the corners of the door opposite the hinge lugs.

In each case the arrangement of the webs is such as to carry stresses imposed upon the door structure to hinges by means of which the doors are connected with the car body. 105

I claim:

1. A door forming a portion of the bottom of a railway car of the dumping type

- consisting of an integral casting having a smooth upper surface and formed on its lower surface with depending marginal flanges, one of said flanges being formed 5 with hinge lugs.
2. A door forming a portion of the bottom of a railway car of the dumping type consisting of an integral casting having a smooth, upper surface, depending marginal flanges one of which is formed with hinge lugs, and reinforcing webs which terminate substantially at said lugs.
3. A door forming a portion of the bottom of a railway car of the dumping type consisting of an integral casting having a smooth upper surface, depending marginal flanges one of which is formed with hinge lugs, and diagonally disposed reinforcing webs which terminate substantially at said 20 lugs.
4. A door forming a portion of the bottom of a railway car of the dumping type consisting of an integral casting having a smooth upper surface and formed at one side 25 with hinge lugs and on the lower surface with reinforcing webs.
5. A door forming a portion of the bottom of a railway car of the dumping type consisting of an integral casting formed on its 30 under surface with marginal flanges, a cen-
- tral boss, and reinforcing webs extending from said boss to the flanges.
6. A door forming a portion of the bottom of a railway car of the dumping type consisting of an integral casting formed on its 35 under surface with marginal flanges, a central boss, and reinforcing webs extending from said boss to the corners and edges of the door.
7. A door forming a portion of the bottom 40 of a railway car of the dumping type consisting of an integral casting formed on its under surface with a centrally disposed boss and reinforcing webs extending from said boss to the edges of the door.
8. A door forming a portion of the bottom 45 of a railway car of the dumping type consisting of an integral casting having a smooth upper surface, formed with a continuous depending, marginal flange extending around all four sides of the door, a pair of hinge lugs on one side of the flange, a centrally disposed boss on the under side of the door, diagonally arranged webs extending from the boss to the corners of the door, and webs bridging the space between the side of the marginal flange having the hinge lugs and the adjacent reinforcing webs and aligned with said hinge lugs.

WALTER P. MURPHY.
